COMBINATION LADDER STOOL

David Greene, Brooklyn, N. Y., assignor to Esmco
Auto Products Corporation, Brooklyn, N. Y., a
corporation of New York

Application June 21, 1945, Serial No. 600,702

7 Claims. (Cl. 155—42)

1

This invention relates to what are generally known as ladder stools. More particularly, the invention deals with a structure of this type and kind, wherein one step of the ladder comprises an L-shaped step frame slidably engaging the leg portion of the stool and, wherein, the stool includes a lift-top adapted to form a backrest for the seat of the stool and to automatically advance the step to operative position.

The novel features of the invention will be best understood from the following description, when taken together with the accompanying drawing, in which certain embodiments of the invention are disclosed, and in which the separate parts are designated by suitable reference characters in each of the views and, in which:

Fig. 1 is a side view of a stool structure made according to my invention with part of the construction broken away and showing parts in extended position in dot and dash lines.

Fig. 2 is a front view of the structure shown in Fig. 1.

Fig. 3 is a rear edge view of a part of the construction shown in Fig. 1 on an enlarged scale; and

Fig. 4 is a section on the line 4—4 of Fig. 3.

The stool, in the construction shown, comprises a main seat 10 having a pair of U-shaped leg frames 11, 11' which may be of tubular construction to minimize the weight of the stool and these frames are bolted or otherwise secured, as indicated at 12. The lower ends of the frame 11, 11' terminate in rubber feet 13 to retain the stool against accidental displacement, particularly on a smooth surface, as well as to protect a surface on which the stool is arranged. Secured to the inner surface of the legs of the frames 11, 11' and bridging the rear leg members of these frames is a horizontal reinforcing member 14. Opposed sides 15, 15' of the member 14 are of channel cross-sectional form back to a point, indicated at 16 in Fig. 1 of the drawing. Beyond the channel structure, the member 15 is of angle-iron cross-sectional form. The channels 15, 15' form supports and guides for an L-shaped step member 17, which comprises a step board 18 and a pair of L-shaped leg members 19, 19' secured to the board 18 by bolts, as seen at 20, and braced adjacent their lower ends by a brace rod 21, note Fig. 1. It is here to be noted that the forward leg members of the frames 11, 11' are also joined and braced by a rod 22, which is slightly offset in order to bring the legs 19 within a fully collapsed position within the front members of the leg frames 11, 11', as illustrated in the full line posi-

2

tion of Fig. 1. At the lower ends of the leg members 19, 19' are preferably disposed domes-of-silence 23 or other similar antifrictional ends providing a free movement of the legs 19, 19' over a supporting surface.

Arranged upon and normally disposed over the main seat 10 is a supplemental seat 24 which also serves as a backrest when the latter is in raised position. The seat 24 is hinged to the seat 10, as

10 seen at 25, a pair of hinges being employed and spaced along the rear edge of the seat 10, the hinge being countersunk in the seat 10, as well as in the seat 24. The upper surface of the seat 10 has on its forward edge cushioned bumpers 26 to 15 support the seat 24 in spaced parallel relationship to the seat 10 and above a tread surface of rubber or other material 27 on the top of the seat 10. Here it is to be noted that the step board 18 has a similar tread surface 28 of cushioned rubber.

20 The rear edge of the seat 24 has a socket 29 for receiving a substantially U-shaped bracket 30 supporting a pivot pin 31 forming a pivotal coupling for a substantially L-shaped lever 32.

Secured to the lower surface of the seat 10 substantially centrally of the sides thereof and adjacent the rear portion of the seat is a U-shaped bracket 33, to which is pivoted an arm 34, the lower end of which is pivotally coupled to a link 35 pivoted to a bracket 36 on the step board 18 30 similar to the bracket 33.

The lever 32 is pivoted to the arm 34 adjacent the upper end thereof, as seen at 37. This construction is such that, in the normal collapsed position of the stool, the lever 32, arm 34 and link 35, are all contained within the outer boundaries of the stool structure, including the supplemental top 24 thereof. In this position, the step member 17 is also substantially within these boundaries.

40 It will thus be seen that, in raising the supplemental seat 24 into its perpendicular backrest position, partially indicated in dot and dash lines in Fig. 1, the lever 32 will actuate the arm 34 and the link 35 will automatically advance the step member 17 forwardly into a position substantially similar to that shown in dot and dash lines in Fig. 1. In like manner, again lowering the supplemental seat 24 will retract the step member 17.

Considering Fig. 2 of the drawing, it will appear 50 that the supplemental seat 24 is of greater width than the seat 10. Secured to the lower surface of the seat 24, at opposed sides and forwardly of the hinges 25, are brackets 38, 38' and to these brackets are pivoted brace and lock links 39, 39' having knob or finger-piece ends 40, 40'. The

links 39, 39' each have elongated apertures 41 offset upwardly at their forward ends, as seen at 42. Passed through the apertures 41 are headed pins or screws 43, one of which is shown in Fig. 1 of the drawing which guide the links 39, 39' as the seat 24 is moved into the raised position and, in this operation, the pins or screws 34 are automatically drawn into the offsets 42 and, thus, will lock the seat 24 in its raised backrest position. The purpose of this construction is to not only maintain the backrest in the raised position against accidental lowering, but also to support the step member 17 permanently in its extended position. Thus, in the operation of applying the foot to the step member 17, this step cannot be forced inwardly in the channels. In order to lower the backrest, the two side links 39, 39' must be raised through the medium of the knobs or finger-pieces 40, 40' and then the supplemental seat 24 may be lowered and the step 18 drawn inwardly.

In referring to the step member 17 above, reference is, of course, had to the complete step frame 17, as the legs 19, 19' move in unison with the step.

It will be understood that, in one use of the chair or stool construction, the same may be used as a stool, with the parts in the full line position, in which event, the supplemental seat 24 becomes the primary seat of the stool. On the other hand, in moving the parts into the dotted line position, the device may be simply used as a seat, in which event the member 24 becomes a backrest and the step member 17 becomes a footrest.

In this latter position, the device becomes a step ladder, where the member 17 becomes the first treadle or step of the ladder and the main seat member 10 becomes the second step of the ladder. In this use, the supplemental seat 24, in its backrest position, forms a stop limiting movement of the feet on the step. This prevents overstepping and produces a guard in this respect. The raised supplemental seat may be also used as a support for articles or tools in the use of the ladder.

Considering Fig. 1 of the drawing, it will appear that the step 18 extends, in its closed position, to substantially the full length of the channels 15, 15', as partially seen at 18' in said figure, thus when the step member 17 is in its extended position, a firm support of this member in the chair or stool-frame is maintained in addition to the support contributed by the legs 19, 19'.

It will be understood that, by keeping all of the operative parts of the stool or chair structure within the outer boundaries of the frames 11, 11' and the larger area of the supplemental top member 24, a very simple packaging of the structure is accomplished for shipment and transportation and also in the storage of the stool in the home. Further, by centralizing the link and lever coupling, an even and balanced action is provided between the supplemental top 24 and the step member 17.

Having fully described my invention, what I claim as new and desire to secure by Letters Patent is:

1. A chair of the class described comprising two U-shaped leg frames, a main seat joining and spacing upper ends of said frames, a reinforcing U-shaped frame bridging the leg members of the leg frames and joining two leg members of each leg frame, said reinforcing frame

having channelled side portions, a step member slidably engaging said channelled side portions, said step member having substantially L-shaped leg portions, a supplemental seat normally arranged over and hingedly coupled with the main seat, a lever pivoted to the supplemental seat, an arm pivoted to and extending downwardly from the main seat to which said lever is pivoted, a link pivotally coupled with said step member and with the end of said arm providing linkage coupling between the supplemental seat and the step member whereby movement of the supplemental seat into raised position will automatically extend the step member forwardly with respect to the leg frames, and means bracing the supplemental seat in its raised position and checking inward movement of the step member.

2. A chair of the class described comprising two U-shaped leg frames, a main seat joining and spacing upper ends of said frame, a reinforcing U-shaped frame bridging the leg members of the leg frames and joining two leg members of each leg frame, said reinforcing frame having channelled side portions, a step member slidably engaging said channelled side portions, said step member having substantially L-shaped leg portions, a supplemental seat normally arranged over and hingedly coupled with the main seat, a lever pivoted to the supplemental seat, an arm pivoted to and extending downwardly from the main seat to which said lever is pivoted, a link pivotally coupled with said step member and with the end of said arm providing linkage coupling between the supplemental seat and the step member whereby movement of the supplemental seat into raised position will automatically extend the step member forwardly with respect to the leg frames, and means bracing the supplemental seat in its raised position and checking inward movement of the step member.

3. A chair of the class described comprising two U-shaped leg frames, a main seat joining and spacing upper ends of said frames, a reinforcing U-shaped frame bridging the leg members of the leg frames and joining two leg members of each leg frame, said reinforcing frame having channelled side portions, a step member slidably engaging said channelled side portions, said step member having substantially L-shaped leg portions, a supplemental seat normally arranged over and hingedly coupled with the main seat, a lever pivoted to the supplemental seat, an arm pivoted to and extending downwardly from the main seat to which said lever is pivoted, a link pivotally coupled with said step member and with the end of said arm providing linkage coupling between the supplemental seat and the step member whereby movement of the supplemental seat into raised position will automatically extend the step member forwardly with respect to the leg frames, and means bracing the supplemental seat in its raised position and checking inward movement of the step member, said last named means comprising a lock link pivoted to the supplemental seat and having a sliding pivotal coupling with the main seat.

4. A chair of the class described comprising two U-shaped leg frames, a main seat joining and spacing upper ends of said frames, a reinforcing U-shaped frame bridging the leg members of the leg frames and joining two leg members of each leg frame, said reinforcing frame

of the leg frames adjacent the lower ends thereof, and said last named means comprising an inwardly offset bar forming a recess for the reception of the legs of the step member in nesting the step member and legs thereof within the bounds of the chair frame.

4. In combination stool ladders of the class described, a stool frame, opposed channels in said frame, a step member slidably engaging said channels, said step member including leg portions having domed lower ends for sliding over the surface of a support, means movably supported on the stool frame and coupled with said step member for moving the step member into extended and contracted positions in the stool frame, and said means including means for retaining the step member against accidental displacement when in extended position.

5. In combination stool ladders of the class described, a stool frame, opposed channels in said frame, a step member slidably engaging said channels, said step member including leg portions having domed lower ends for sliding over the surface of a support, means movably supported on the stool frame and coupled with said step member for moving the step member into extended and contracted positions in the stool frame, said means including means for retaining the step member against accidental displacement when in extended position, and means providing a complete nesting of the step member including the legs thereof within the boundaries of the stool frame.

6. A combination stool and step ladder comprising a stool frame consisting of leg members and a top main seat, means slidably supporting a step member in the frame to nest within the bounds of the frame and adapted for extension forwardly of the lower portion of the frame, a mechanism for moving the step member into ex-

tended and collapsed positions comprising a link member arranged within the frame and pivoted to the main seat and to said step member, a supplemental seat member swingably coupled with the main seat member, and a link coupling said supplemental seat member with said link member to automatically extend the step member in moving the supplemental seat into raised position.

7. A combination stool and step ladder comprising a stool frame consisting of leg members and a top main seat, means slidably supporting a step member in the frame to nest within the bounds of the frame and adapted for extension forwardly of the lower portion of the frame, a mechanism for moving the step member into extended and collapsed positions comprising a link member arranged within the frame and pivoted to the main seat and to said step member, a supplemental seat member swingably coupled with the main seat member, a link coupling said supplemental seat member with said link member to automatically extend the step member in moving the supplemental seat into raised position, means for bracing the supplemental seat member in raised position, and said last named means including means for retaining the step member in extended position.
